(57) **CLAIM**

The ornamental design for a interactive display device, as shown and described.

DESCRIPTION

FIG. 1 is a front perspective view of the interactive display device showing our new design;

FIG. 2 is front view of FIG. 1;

FIG. 3 is a back view of FIG. 1;

FIG. 4 is a left side view of FIG. 1;

FIG. 5 is a right side view of FIG. 1;

FIG. 6 is a top plan view of FIG. 1; and,

FIG. 7 is a bottom plan view of FIG. 1.

The broken lines showing features on the front and back are included for the purpose of showing portions that form no part of the claimed design.

1 Claim, 5 Drawing Sheets

FIG. 1

FIG. 2

FIG. 3

FIG. 4

FIG. 5

FIG. 6
